CLAIM

The ornamental design for a lighter holder with pipe tools, as shown and described.

DESCRIPTION

FIG. 1 is a top perspective view of a lighter holder with pipe tools thereof;

FIG. 2 is a top plan of FIG. 1 thereof;

FIG. 3 is a top plan view with tools closed thereof;

FIG. 4 is a bottom plan view with pipe tools closed thereof;

FIG. 5 is a right elevation view thereof;

FIG. 6 is an inverted front elevation view thereof;

FIG. 7 is an inverted rear elevation view thereof; and,

FIG. 8 is an environmental drawing showing the lighter holder with pipe tools being used as a bottle opener.

The broken lines showing a lighter, bottle and bottle cap depict environmental subject matter only and form no part of the claimed design.
